UNITED STATES PATENT OFFICE.

LOUIS SANDERS, OF BROOKLYN, NEW YORK.

DESIGN FOR A BELT.

SPECIFICATION forming part of Design No. 26,756, dated March 16, 1897.

Application filed December 9, 1896. Serial No. 615,061. Term of patent 3½ years.

To all whom it may concern:

Be it known that I, LOUIS SANDERS, a citizen of the United States, residing at Brooklyn, in the county of Kings and State of New York, have invented and produced a new and original Design for a Belt, of which the following is a specification, reference being had to the accompanying drawings, forming a portion thereof, in which—

Figure 1 is a perspective view of the improved belt. Fig. 2 is a plan view thereof, and Fig. 3 is a section which is taken on the line 3 3 of Fig. 2.

The leading feature of the design consists of a belt in which the upper and lower lines are drawn parallel with each other from the sides in direction of the front and the rear,

the upper and lower lines inclining downward from the sides to the front and rear, the corresponding lines meeting at an obtuse angle, forming a point B at the front and a point B' at the rear. 20

A minor feature of the design consists in the rear section 10 of the belt being connected with the front section 11, the connection between the two sections 10 and 11 being brought about by means of two buckles 12. 25

I claim—

The design for a belt herein shown and described.

LOUIS SANDERS.
